WITNESS:

UNITED STATES PATENT OFFICE.

ELWIN C. WEBBER, OF SALT LAKE CITY, UTAH.

EGG-CASE FILLER.

Application filed February 18, 1922. Serial No. 537,499.

To all whom it may concern:

Be it known that I, ELWIN C. WEBBER, a citizen of the United States, residing at Salt Lake City, in the county of Salt Lake and State of Utah, have invented new and useful Improvements in Egg-Case Fillers, of which the following is a specification.

This invention relates to an egg case filler, the general object of the invention being to 10 provide means for supporting the eggs on end, thus reducing the liability of breakage as it is a well known fact that the central part of the shell is thinner than the end parts.

15 Another object of the invention is to make the supporting means adjustable so that they will support different sizes of eggs and to so form such supporting means that the entire central circumference of the egg will be engaged thereby so as to reduce breakage to a minimum even though the cases are so placed that the eggs are supported on their sides.

This invention also consists in certain other features of construction and in the 25 combination and arrangement of the several parts, to be hereinafter fully described, illustrated in the accompanying drawings and specifically pointed out in the appended claim.

30 In describing my invention in detail, reference will be had to the accompanying drawings wherein like characters denote like or corresponding parts throughout the several views, and in which:—

35 Figure 1 is a top view, with parts broken away, of the invention.

Figure 2 is a section on line 2—2 of Figure 1.

Figure 3 is a view of the egg supporting 40 member.

Figure 4 is a view of one of the compartment members.

Figure 5 is a sectional view showing how the fillers are placed in the crate.

45 Fig. 6 is a sectional view showing the ring shaped flexible part.

As shown in these views the supporting means for each layer of eggs in the crate A comprises a lower compartment member 1, 50 an upper compartment member 2 and a partition 3 placed between the two compartment members and having holes 4 therein for receiving the eggs, the eggs projecting into the compartments of the compartment members. Each compartment member is com-

posed of the strips 5 and 6 which extend across each other and are slotted, as at 7, so that the edges of the strips lie in the same plane. The partition 3 has the holes so formed that they will register with the compartments in the upper and lower members and a circular cut 8 is made in the partition around each opening and concentric therewith, said cut extending part-way through the partition so as to provide a ring shaped flexible part 9 for engaging the egg around its center, thus supporting the same even when the crate is placed upon its side. These flexible parts also permit the partition to support eggs of different sizes as said flexible parts will adjust themselves to the eggs. Sheets 10 are placed between the layers of eggs and said sheets, compartment members and the partitions may be formed of any suitable material, such as straw-board.

75 As will be seen the partition 3 will prevent the eggs from engaging the walls of the compartments and will hold them in upright position when the crate is resting upon its bottom or top and will also prevent the eggs from resting upon the sides if the crate should be placed upon one of its sides. As the egg is supported at its center, when the case is placed upon one of its sides, there is little danger of breakage as the weight and 80 jars or shocks due to the handling of the case is distributed over the entire circumference of the egg where the flexible part engages it. This partition also prevents the movement of the eggs and the flexible parts permit eggs 85 of various sizes to be crated.

90 It is thought from the foregoing description that the advantages and novel features of my invention will be readily apparent.

I desire it to be understood that I may 95 make changes in the construction and in the combination and arrangement of the several parts, provided that such changes fall within the scope of the appended claim.

What I claim is:—

An egg crate filler comprising a pair of compartment members, a partition separating the members and having openings therein, said openings having flexible walls, said walls being formed by cutting circles partly 105 through the partition concentric to the openings.

In testimony whereof I affix my signature.

ELWIN C. WEBBER.
